UNITED STATES PATENT OFFICE.

ELMER A. SPERRY, OF BROOKLYN, NEW YORK.

MILITARY SEARCHLIGHT.

1,412,757.

Specification of Letters Patent. Patented Apr. 11, 1922.

Application filed May 25, 1916. Serial No. 99,715.

To all whom it may concern:

Be it known that I, ELMER A. SPERRY, a citizen of the United States of America, residing at borough of Brooklyn, New York city, in the county of Kings and State of New York, have invented certain new and useful Improvements in Military Searchlights, of which the following is a specification.

This invention relates to the art of illuminating battlefields. Modern warfare has developed the range and accuracy of guns to such an extent that it has been found impossible to employ searchlights in connection with trench warfare on the European battlefields, since almost as soon as the light was turned on, it would be shot to pieces by the enemy's gun fire.

The object of this invention is to devise a searchlight adapted for use in connection with any form of land fortifications, such as trenches, inland forts or coast defense fortifications.

Referring to the drawings in which what I now consider to be the preferred forms of my invention are shown: Fig. 1 is a side elevation of a searchlight, constructed according to my invention. Fig. 2 is a rear elevation of the same. Fig. 3 is an enlarged section of the top of the mast or post. Fig. 4 is a sectional detail of the bottom of the post, the section being taken on line 4—4, Fig. 5. Fig. 5 is a side elevation of the same. Fig. 6 is a rear elevation of a modified mirror. Fig. 7 is a side elevation of the same. Fig. 8 is a sectional view of the searchlight, the section being taken on line 8—8, Fig. 10. Fig. 9 is an enlarged plan view of the pan used to prevent hot particles of carbon from falling on the mirror. Fig. 10 is a section on line 10—10, Fig. 2. Fig. 11 is detail of the scale on the elevating mechanism.

According to my invention, I design the lights so that the searchlight itself 1 may be placed entirely below the ground in a sheltered pit 2 or behind a parapet or the like. The searchlight is mounted in a normally vertical position, so that the beam is projected vertically upward. Positioned above the lamp on a post or mast 3 is a reflector or mirror 4, preferably inclined at about 45° to the vertical, so that the reflected beam will be approximately hori-

zontal. The mast is preferably made of a plurality of sections 64 and 65 so that it may be readily disassembled.

The mirror may be made of the usual material or it may be made of polished metal, so as not to be damaged to any great extent by small bullets and fragments of shells.

In order to effect changes in the elevation of the beam, both the searchlight and mast are mounted on horizontal trunnions 66, 7 in brackets 8, 9, the mast being rigidly clamped to the drum by means of one or more brackets 10. Preferably the drum is placed on the opposite side of the pivots from the major portion of the mast and the mirror so as to counterbalance the structure. The bracket 11 which supports trunnion 7 is provided with a large segmental gear 12 with which the pinion 13 on stud shaft 14 meshes. This gearing is rotated from handle 15 by means of a pinion 17 on the shaft of said handle and the gear 18 on said stud shaft 14. The segmental gear 12 is preferably provided with indications 16 so that the operator may know the elevation of the beam. The scale is graduated in each direction from the vertical or zero position. Preferably additional, complementary graduations 60 are provided, (see Fig. 11) for a purpose hereinafter explained. The reference pointer 61 for this scale, as well as the pointer 62 for the scale 63 on the rotatable base 20 is preferably made adjustable so that any errors made in the positioning of the mirror at the proper angle can readily be compensated for by moving the reference indices. Both scales are preferably divided, or made in two parts which read from zero in both directions. This is especially important on scale 63, since it enables the operator to obtain like readings on both sides of the base.

The two brackets 8 and 9 are mounted on a base 20, rotatable in azimuth, whereby the entire searchlight may be revolved in the usual manner. I also prefer to provide means whereby the beam may be thrown directly upward from the searchlight without employing the mirror 4 so that the searchlight may be employed to search out objects at considerable altitude such as aeroplanes and other aircraft. For this purpose the mirror is secured to a bracket 21 which is

rotatably mounted on the top of post 3. A small rod 22 extending axially through said post serves to rotate the mirror from its position in the beam to a position without the beam (see dotted lines, Fig. 2). At its lower end rod 22 is provided with a handle 23 by means of which the mirror is rotated. A snap button 24 may also be secured to the rod to lock the mirror in the desired position either within or without the beam by engaging depressions 124 or 125 in the bottom of foot 128. The post is preferably made adjustable so that the entire mirror can be lowered to the ground for inspection or renewal. For this purpose the two clamps 25 and 26 by means of which the post is secured to bracket 11, are hinged at 26' and 27' respectively, so as to swing outwardly and release the post, wing 20 nuts 27 being provided to hold the clamps in place. Upon release of the clamps the entire post may be revolved upon the foot 128. Release of the clamps also permits rotation of the post on its own axis for the purpose of adjustment.

No attempt has been made to disclose a complete searchlight mechanism as I may use in my lamp any form of light source adapted to work in a vertical position. I prefer, however, to employ the type of light disclosed in my copending application for improvements in searchlights, Serial No. 21,661, filed April 16th, 1915. This type of light not only gives a very much greater beam candlepower than any other, but also is adapted to work in any position, horizontal, vertical or inclined. In Fig. 8 the positive holder is shown at 30, and the negative holder at 31.

In order to prevent the hot particles of carbon, copper or other material from dropping onto the polished surface of the mirror from the electrodes and electrode holders I prefer to employ a shield or pan 32 which may be kept below the arc by being pivotally supported so as to hang in a vertical position irrespective of the position of the drum. Preferably this pan is of openwork metal such as fine wire gauze, preferably of open mesh so that a minimum amount of light may be shut off thereby. Mica or similar transparent material may also be used. In the embodiment shown the pan is suspended from small pivoted arms 33, 34. These arms normally rest against pins 35 in the side of the drum, but when the drum is tilted to more than a predetermined angle the arms revolve on the pivots and permit the pan to drop without the zone of light 60 from the mirror (see dotted lines in Fig. 10). In other words when the drum is tilted through such an angle that the hot particles would not strike the mirror the pan is removed preferably automatically from in front of the mirror to the dark space be-

tween the edge of the mirror and the drum. To reset the levers, the operator turns the finger pieces 36 which are secured to the shafts 37 of levers 33 and 34. The points of suspension are preferably in line with 70 the arc 50.

In order to ventilate and properly cool my searchlight in this position, there is provided an exhaust fan 38 mounted in a housing 38' on one side of the drum. The inlet 75 openings 39 and 40' in one side of the searchlight are so arranged that a circulating current of air will pass over the front window 40 and will sweep over the surface of the projector 41 without causing flickering of the light. For this purpose, suitable guiding shields 42 and 43 may be provided. The drafts of air thus created not only keep the reflector and front door cool but serve to wash them clean of smoky deposits and 85 particles which otherwise would seriously lessen the efficiency of the lamp after a few hours' run.

A modified form of mirror mounting is shown in Figs. 6 and 7. According to this 90 form of the invention the elevation of the beam is adjusted by tilting the mirror 4' on the post 3 by means of a chain 45 or other means readily accessible from below the mirror. In this form of the invention also 95 it is unnecessary to provide means to rotate the mirror without the beam since very little shadow will be caused by the mirror if it is turned into a position parallel with post 3, as shown in Fig. 7.

One important use of the invention will be illustrated by supposing that the searchlight when in the position shown in Figs. 1 and 2 picks up a hostile aeroplane approaching in the distance. As the aeroplane comes 105 nearer and climbs higher and higher in the zenith, the searchlight is tilted backwardly by means of handle 15 until it is tilted through an angle of say 45°. The mirror may then be quickly removed from the beam 110 of light by turning handle 23, and the searchlight quickly and accurately brought to bear upon the aeroplane directly by rotating or tilting the searchlight in the opposite direction. The operator can thus keep 115 the searchlight directly upon the machine until it again drops below a predetermined position when the mirror can be again brought into play and the searchlight again quickly tilted.

By securing the mast to the searchlight and oscillating or turning them together, another important advantage is secured over the usual searchlight. This is due to the fact that the apparent source of light, as seen 125 from a distance, would move through a considerable distance every time the lamp was turned, so that it would be very difficult to tell where the real light was.

In accordance with the provisions of the 130

patent statutes, I have herein described the principle of operation of my invention, together with the apparatus, which I now consider to represent the best embodiment 5 thereof, but I desire to have it understood that the apparatus shown is only illustrative and that the invention can be carried out by other means. Also, while it is designed to use the various features and elements in the 10 combination and relations described, some of these may be altered and others omitted without interfering with the more general results outlined, and the invention extends to such use.

15 Having described my invention, what I claim and desire to secure by Letters Patent is:—

1. A military searchlight comprising a drum supported on a substantially horizontal axis in a normally vertical position, a reflector, means for supporting said reflector aloft journaled for oscillation about said horizontal axis, means whereby the drum and supporting means may be rotated about 25 said axis, and a scale for indicating the elevation, said scale being provided with major and complementary angular graduations.

2. The combination with a normally vertical searchlight, of a mast mounted adjacent said light, a reflector supported on said mast, and means whereby said reflector may be moved within and without the searchlight beam.

3. The combination with a normally vertical searchlight, of a mast mounted adjacent said light, a reflector swivelled about a normally vertical axis on said mast, and means whereby said reflector may be moved within and without the searchlight beam.

40 4. A military searchlight comprising a rotatably mounted base, a searchlight supported in a normally vertical position on said base, a reflector supported above said searchlight and means whereby said reflector may be placed within or without the beam.

5. The combination with a normally vertical searchlight, of a mast mounted adjacent said light, a reflector supported on said mast, a shaft extending parallel said mast and 50 provided with manipulating means, said shaft being secured to said reflector adjacent its top whereby the reflector may be turned without the beam.

6. The combination with a normally vertical searchlight, of a hollow mast mounted adjacent said light, a reflector supported on said mast, a shaft extending through said mast and provided with manipulating means, said shaft being secured to said reflector adjacent its top whereby the reflector may be turned without the beam.

65 7. The combination with a searchlight mounted so that it may assume a vertical position including a projector and a source of light, of a perforated or openwork catch

pan pivotally supported between the said light source and the projector to protect the latter.

8. The combination with a searchlight pivotally mounted so that it may assume a vertical position including a projector and a source of light, of a catch pan pivotally suspended between the said light source and the projector to protect the latter, the pivotal axis of support for said pan being approximately 70 in horizontal alignment with the said source.

9. The combination with a searchlight pivotally mounted so that it may assume a normally vertical position including a drum, a projector and a source of light, of a catch 80 pan suspended from opposite points adjacent the drum between the said light source and the projector to protect the latter.

10. The combination with a searchlight drum and projector suspended for oscillation about a horizontal axis, of an arm pivoted in the side of the drum, a catch pan suspended from adjacent the free end of said arm, a stop for supporting said arm in an inclined upstanding position, whereby said 90 arm will revolve and drop the pan when the searchlight is turned through a predetermined angle.

11. The combination with a searchlight pivotally mounted in a normally vertical position including a projector and a source of light, of a catch pan suspended between the said light source and the projector to protect the mirror, and means for removing said 95 pan to a point without the beam when the searchlight is turned through a predetermined angle.

12. A searchlight comprising a source of light, a projector, a shield suspended between said source and projector when a vertical line through said source intersects said projector, and means for causing said pan to move out of the path of the light rays passing from said source to said projector as soon as the above mentioned vertical line is 105 beyond the edge of the latter.

13. In combination, a normally vertical searchlight oscillatable about a horizontal axis, a reflector mounted above said searchlight, means connecting said searchlight and reflector for maintaining the latter in the beam of the searchlight and means controlled from a point adjacent said searchlight for removing said reflector from said beam.

14. In a searchlight including a projector 120 and a source of light, a catch pan within said searchlight and means whereby said catch pan may be placed in its inoperative position without the path of the light beam and in its operative positive position to shield 125 the projector in response to changes in the position of the searchlight.

15. In a searchlight including a projector and a source of light, a projector shield located between said light source and said 130

projector, and means responsive to the position of the searchlight for removing said shield from its operative position to a position without the light beam.

5 16. The combination of a searchlight having a drum and supported for oscillation on horizontal pivots, of a mast, a foot for sup-

porting the bottom of the mast, and detachable clamping means for securing said mast to said foot and searchlight, and a mirror 10 secured adjacent the top of said mast.

In testimony whereof I have affixed my signature.

ELMER A. SPERRY.
